UNITED STATES PATENT OFFICE.

LESLIE ROBERT ANNELL, OF BOISE, IDAHO.

COMBINED PLOW AND BRUSH-CUTTER.

SPECIFICATION forming part of Letters Patent No. 683,242, dated September 24, 1901.

Application filed March 8, 1901. Serial No. 50,280. (No model.)

To all whom it may concern:

Be it known that I, LESLIE ROBERT ANNELL, a citizen of the United States, residing at Boise, in the county of Ada and State of Idaho, have 5 invented certain new and useful Improvements in a Combined Plow and Brush-Cutter; and I do hereby declare the following to be a full, clear, and exact description of the invention, such as will enable others skilled in the 10 art to which it appertains to make and use the same.

This invention relates to weed and brush cutters, and particularly to that class designed for use in cutting sage-brush.

15 The objects of the invention are, first, to provide a cutting attachment for use in connection with sulky-plows which can be readily connected to or removed therefrom; second, to provide novel means for guiding the 20 rear wheel through a connecting-rod taking movement from the tongue of the sulky; third, to provide novel blade-carrying parts comprising a frame of rigid structure which will withstand the strain incident to its use, 25 and, finally, the object of the invention is the production of a brush-cutting attachment for sulky-plows which will possess advantages in points of efficiency and inexpensive structure.

30 With the above and other objects in view the invention consists in the details of construction and in the arrangement and combination of parts to be hereinafter more fully set forth and specifically claimed.

35 In describing the invention in detail reference will be had to the accompanying drawings, forming part of this specification, wherein like characters denote corresponding parts in the several views, in which—

40 Figure 1 is a plan view of a sulky-plow with an attachment embodying the invention. Fig. 2 is a view in side elevation. Fig. 3 is a view in elevation of a fragment of the frame. Fig. 4 is a view in perspective of several elements of the rear truck-frame and the beam for connecting the rear truck to the sulky. 45 Fig. 5 is a detail view in perspective of a connecting-rod and its turnbuckle detached. Fig. 6 is a perspective view of the knives and 50 the guide-strips.

In the drawings, 1 indicates the sulky of an ordinary plow, and 2 the beam thereof, which

is the shape of an I-beam in cross-section, in the channel of which is fitted the connection 3. This connection 3 is given a quarter-twist and 55 is provided with a depending end 4, to which the rear frame 5 is attached through the medium of the clips 6, which pass through suitable coinciding apertures of the frame and depending ends, as fully shown in Fig. 4. The 60 clips also bind a bearing 7 to the frame at the rear, in which is rotatably mounted a standard 8. A collar 9 is fixed on the standard to limit its downward movement, and a bracket 10, fixed to the standard, extends 65 downwardly on an incline. A stud 11 is carried by the bracket, and a ground-wheel is mounted on the stud. The bracket is provided with an extension 12, having an end 13 standing at right angles over the periphery 70 of the ground-wheel 14. A scraper or cleaner 15 is secured to the end 13 and bears against the ground-wheel to prevent accumulation thereon.

A sectional rod 16, connected by a turn-buckle 17, extends from an arm 18 of the standard 8 to the arm 19 on the sulky-tongue, the said connecting-rod passing diagonally across the longitudinal center of the frame, so that the movement of the tongue is im- 75 parted to the standard, which turns in its bearings and guides the rear truck.

The frame 5 has depending portions 20, with their extremities 21 inclined outwardly and slightly rearwardly in order that the knives 85 22 may be attached thereto and assume an inclined position with their cutting edges outside of the plane of their upper edges. The knives converge toward the front of the frame and are provided with angular ends 23. A 90 guide-strip 24 is bolted to the sheath 25 and is of such width as to extend below the plane of the cutting edges of the knives. The end of the guide-strip is provided with a depending shovel-like point 26, which forms a furrow for the guide-strip. Just back of the point 26 the guide-strip is provided with an opening 27, in which the angular ends of the blades or knives abut, said ends being bolted to the shovel-like end of the guide-strip and are further held through the engagement of the end of the blades in the opening 27. By an inspection of Fig. 2 it will be seen that as the guide-strip travels in the furrow lateral

displacement will be prevented when the knives are in action. Braces 28 extend from the connection 3 to the depending members 20 of the rear frame for giving rigidity to the 5 structure.

The seat 29 is supported by a spring 30, bolted to the connection 3 at the rear.

Having thus described the invention, what I claim as new, and desire to secure by Letters 10 Patent, is—

1. In a weed-cutter, the combination with the sulky, beam and sheth of a plow, of an attachment carrying cutter-blades, means for connecting the attachment to the beam and 15 sheth a caster-wheel secured to the attachment and a rod connected to the sulky and attachment for guiding the wheel.

2. In a weed-cutter, the combination with the sulky, of a frame, a connection between 20 the sulky and frame, cutting-blades attached to the frame at the rear and converging at the front, a guide-board having its lower edges depending below the edges of the cutter-blades and means for joining the parts together, substantially as described.

3. The combination in a weed-cutter, of a truck, cutter-blades V-shaped in plan, a guide-board depending below the edges of the cutter-blades and means for connecting the parts 30 with the truck, substantially as described.

4. The combination in a weed-cutter, of cutter-blades V-shaped in a plan, a guide-board intermediate of and extending rearwardly from the apex of the cutter-blades to which 35 the cutter-blades are secured at their forward ends and a shovel-like extremity on the forward portion of the guide-board, substantially as described.

5. The combination in a weed-cutter of a sulky having a beam and sheth, a guide-board 40 secured to the sheth, said guide-board having a slot in its forward end and a shovel-like projection, cutter-blades with their lower edges

above the plane of the lower edge of the guide-board, said cutter-blades having angular ends 45 lying in the slot of the guide-board and bolted to the shovel-like extension, a frame having depending members to which the rear ends of the cutter-blades are secured, a connection between the plow-beam and the frame, a rear 50 truck for supporting the frame, an adjustable connecting-rod placed diagonally of the longitudinal center, and arms on the sulky-tongue and the standard of the rear truck to which the connecting-rod is pivoted, substantially 55 as described.

6. In a weed-cutter, the combination with the sulky-beam and sheth of an ordinary sulky-plow, of a guide-board secured to the sheth and having a shovel-like end and an 60 opening back of the shovel, cutter blades having angular ends lying in the openings and bolted to the shovel-like end, said blades diverging toward the rear and set with their cutting edges outside of the vertical plane of 65 their top edges, a frame having depending members with laterally and rearwardly disposed extremities, to which the rear ends of the cutter-blades are secured, a connection between the frame and the beam, a journal-bearing secured on the frame, a bracket having a standard journaled in the bearing a wheel on the bracket, a scraper on an extension of the bracket, bearing against the periphery of the wheel, arms on the standard and on the tongue 70 of the sulky, an adjustable connecting-rod stationed diagonally across the longitudinal center and connecting the arms as and for the purpose described.

In testimony whereof I affix my signature 80 in presence of two witnesses.

LESLIE ROBERT ANNELL.
